HAIR CURLER

Abraham Goodman, Brooklyn, N. Y., assignor to
Delamere Company, Inc., a corporation of Del-
aware

Application March 27, 1937, Serial No. 133,358

6 Claims. (Cl. 132—41)

The present invention relates to hair curlers, and more particularly to curlers of the type having a hair rolling element on which the ends of hair are gripped prior to rolling, and having a hinged clamp which is swung down and fastened over the rolled hair to prevent the hair from unrolling or uncurling.

One of the principal objections to this type of curler is that it does not permit of winding the 10curls tight to the scalp or head.

It is an object of this invention to provide an improved curler of this type wherein the clamp is mounted in a guideway for rotation relatively to the hair rolling element as well as for swinging movement in respect thereto, thus providing a curler that will permit of winding curls tightly to the scalp.

A further object is to provide a curl construction in which the clamp is revolvably mounted in a guideway which is set and maintained in fixed 20 relation to the hair rolling element so as to prevent any relative longitudinal movement of the clamp and hair rolling element.

Other objects, advantages, and distinguishing 25 features of the invention will appear more fully from the following description thereof, reference being had to the accompanying drawing, in which:—

Figure 1 is a view in side elevation of the as- 30 sembed hair curler;

Fig. 2 is a view in cross-sectional side elevation of a collar part to be attached to the hair-rolling element by a pin which also serves as a pivot on which to swing a jaw member to and 35 from the rolling element to grip or release the hair;

Fig. 3 is a view in cross-sectional side elevation of a second collar part complementary to, and having a driving fit on the collar part of Fig. 2, 40 whereby with the latter to provide a guideway for revolvable mounting thereon of a clamp;

Fig. 4 is a view in cross-section of a member to which the clamp is pivotally attached, and which serves as a carrier for rotary movement 45 of the clamp in the guideway;

Fig. 5 is a view in cross-sectional side elevation of the assembled elements of Figs. 2, 3 and 4; and

Fig. 6 is a view in cross-section taken on the 50 line 6—6 of Fig. 5.

Referring to the drawing, 9 is a tubular hair rolling element to which is attached by means of a pin 10 a collar 11 that serves as a guideway for revolvably mounting the clamp. The hair 55 rolling element 9 has a pair of flat, spaced wings

12 where it receives the pin 10. Also mounted on pin 10 for pivotal movement to and from the plane of the hair rolling element 9, is a finger or jaw 13. Preliminary to rolling the hair, the ends are inserted and gripped between the jaw 13 and the rolling element 9, and are thereafter held while the hair is being curled. This finger or jaw 13 is preferably of arcuate cross-section conforming to a surface of the hair rolling member 9, but, as shown in Fig. 6, is extended into flat wings 14 for side lapping on the wing extensions 12 of member 9 to allow free swinging movement on the pin 10.

The members 9 and 13 are provided with finger pieces 15 and 16, respectively, extending rearwardly of the fixed collar 11, whereby to swing the two members apart for insertion and release of the hair. A spring 17, bearing at one end against the hair rolling member and at the other end against the jaw, is tensioned normally to force the members together, and to hold them in 20 hair gripping position.

18 is a sleeve having a disc or flange portion 19. This sleeve constitutes one of the parts of the collar or guideway 11. In the sleeve 18, Fig. 2, is shown one of two diametrically opposed holes 20 for the pin 10. This sleeve 18, see Fig. 6, is curved at top and bottom but has flat sides 21 that serve to prevent rotation of parts 9 and 13 with respect thereto, and further serve as side bearings for the wings 14 of the jaw 13. Heads 22 on pin 10 bear against the flat sides 21 of sleeve 18 to prevent lateral displacement of the pin.

The sleeve 18 in addition to carrying the pivot 35 10 of the jaw 13 serves as an element of a mounting or guideway for a clamp. This clamp, see Figure 1, is shown as a loop of wire consisting of two arms 23 and 24 having a connecting part 25 carrying a roller or button 26 adapted to be snapped over and held in the open end of the 40 tubular member 9 when the loop is swung down into the plane of that member. The clamp need not be of loop formation, and means other than a roller 26 may be employed to fasten the same. A great variety of such fastening means are 45 known to the art.

The present invention is concerned particularly with the manner of mounting the clamp upon the rolling element 9 so as to permit of rotation of both the hair rolling element and the hair gripping jaw without corresponding rotary movement of the clamp, and without longitudinal play of the clamp with respect to the rolling element during opening or closing movements 50 55

of the jaw. Thus, when the curl has been rolled close to the head and the clamp swung to clamping position, the rolling element may be further rotated slightly to wind the curl very tight to the scalp.

5 The ends of the arms 23 and 24 of the clamp are pivotally connected or hinged at 27 to opposite sides of a semi-circular carrier strap 28 of a curvature which permit the same to be seated 10 revolvably on the sleeve 29 and which holds the ends of the clamp properly spaced apart. The sleeve 29, see Fig. 3, constitutes the second part 15 of the collar 11, and slides with a driving fit over the sleeve 18. When the collar parts are thus secured, see Fig. 5, the carrier strap 28 for the clamp, which may be previously placed on the sleeve 29, is held revolvably on the sleeve 29 between the flange 19 of the sleeve 18 and the corresponding flange 30 of the sleeve 29.

20 The carrier strap 28 to which the clamp is hinged at 27 is shown of arcuate, semi-circular shape. The discs 19 and 30 may therefore be conveniently provided with overhanging peripheral rims 31 and 32 that hold the carrier 28 against radial displacement. The carrier 28 is 25 shown in Figs. 4 and 5 as of U-shaped cross-section, except at its ends 33, where the sides of the U are cut away and the crosspiece of the U continued to the hinge points 27 of the arms 23 30 and 24, and heads 34 are provided to hold the arms 23 and 24 to the strap 28 clear of the underlying sleeve 29.

35 Various modifications in the construction may be made. Instead of being of arcuate or semi-circular form, the carrier 28 may be a complete circle or other suitable shape. In that case the overhanging rims 31 and 32 may be omitted.

I claim:

40 1. A hair curler comprising a hair rolling element, a hair gripping jaw pivoted thereto, a guideway fixed to the hair rolling element and pivoted to the hair gripping jaw, a carrier revo-

lably mounted in the guideway, and a clamp swingably secured to the carrier.

2. A hair curler comprising a hair rolling element, a hair gripping jaw pivoted thereto, a guideway fixed to the hair rolling element, a pin 5 extending through the guideway and the jaw to make a pivotal connection between the two, a carrier revolvably mounted in the guideway, and a clamp swingably secured to the carrier.

3. A hair curler comprising a hair rolling element, a hair gripping jaw pivoted thereto, a guideway immovably secured to the hair rolling element and pivotally connected to the jaw, and a clamp swingable to and from hair clamping position, said clamp being mounted in the guideway to permit of the hair rolling element and its attached jaw being freely rotated without causing rotation of the clamp.

4. A hair curler comprising a hair rolling element, a hair gripping jaw pivoted thereto, a guideway immovably secured to the hair rolling element at the point of pivotal connection with the jaw, a carrier revolvably mounted in the guideway, a swingable clamp having its ends pivotally secured to the carrier at diametrically opposed 25 points.

5. A hair curler comprising a hair rolling element, a hair gripping jaw pivoted thereto, an annular guideway surrounding and immovably secured to the hair rolling element and pivoted 30 to the hair gripping jaw, and a clamp swingably and revolvably mounted in the guideway.

6. A hair curler comprising a hair rolling element, a hair gripping jaw pivoted thereon, both of said elements having handle portions extending rearwardly beyond the pivot, an annular guideway surrounding and immovably secured to the hair rolling element with the handle portions of both the rolling element and the gripping jaw passing through said guideway, and a clamp 40 swingably and revolvably mounted in the guideway.

ABRAHAM GOODMAN.
